CLAIM

The ornamental design for a drum stick, as shown and described.

DESCRIPTION

FIG. 1 is a top view of a drum stick according to the present invention;

FIG. 2, is a left side elevation thereto, the right side being identical thereof;

FIG. 3 is a bottom view thereof;

FIG. 4 is a left end view thereof; and,

FIG. 5 is a right end view thereof.

The broken line portion of the figure drawings is included to show portions of the article that forms no part of the claimed design.
